(57) **CLAIM**

The ornamental design for interchangeable eyewear assembly, as shown and described.

DESCRIPTION

Some of the features of the interchangeable eyewear assembly are generally similar to features of the assembly depicted in the co-pending and co-owned application Ser. No. 29/495, 219 entitled Interchangeable/Wearable Hinged Display Device Assembly, filed on even date herewith, the disclosure of which is incorporated herein by reference. Additionally, some features of the interchangeable eyewear assembly are respectively generally similar to features depicted in co-pending and co-owned U.S. application Ser. No. 29/494, 817, entitled Wearable Hinged Display Device, filed on Jun. 24, 2014, and U.S. application Ser. No. 29/494,823, entitled Wearable Hinged Display Device, filed on Jun. 24, 2014, the disclosures of both of which are incorporated herein by reference.

FIG. 1 is a front perspective view of interchangeable eyewear assembly according to our design;

FIG. 2 is a front elevation view of the interchangeable eyewear assembly of FIG. 1;

FIG. 3 is a back elevation view of the interchangeable eyewear assembly of FIG. 1;

FIG. 4 is a right elevation view of the interchangeable eyewear assembly of FIG. 1;

FIG. 5 is a left elevation view of the interchangeable eyewear assembly of FIG. 1;

FIG. 6 is a top elevation view of the interchangeable eyewear assembly of FIG. 1;

FIG. 7 is a bottom elevation view of the interchangeable eyewear assembly of FIG. 1; and,

FIG. 8 is another front perspective view of the interchangeable eyewear assembly of FIG. 1.
